UNITED STATES PATENT OFFICE.

ARCHIBALD THOMSON DEWAR, OF LIVERPOOL, COUNTY OF LANCASTER,
ENGLAND.

SHIP'S BOAT.

SPECIFICATION forming part of Letters Patent No. 433,854, dated August 5, 1890.

Application filed November 1, 1888. Serial No. 289,693. (No model.)

To all whom it may concern:

Be it known that I, ARCHIBALD THOMSON DEWAR, freight clerk, a subject of the Queen of Great Britain, and a resident of 16 Stuart 5 Road, Liverpool, in the county of Lancaster, England, have invented new and useful Improvements in Ships' Boats, of which the following is a specification.

The object of my invention is to provide a ship's boat with removable seats, thwarts, and air-cases that are connected to each other in such a manner as to constitute a separate raft-like structure adapted for independent use in an emergency, or which can be placed 10 as a whole in a boat-shell and be removable therefrom all at once to permit the housing of one boat within another; and to these ends my invention consists in the construction and combination of parts hereinafter described and claimed.

Figure 1 illustrates in side elevation an arrangement of the ships' boats and apparatus according to my invention. Fig. 2 illustrates in end elevation the arrangement of ships' 25 boats and apparatus shown in Fig. 1. Fig. 3 is a perspective view of the seats and air-cases when removed from a boat and according to my invention.

Referring to the drawings, three boats A, 30 B, and C are shown, the boat B being placed inside the boat A, and the boat C being placed inside the boat B, the sizes of the boats being such that this can be done. The thwarts D, seats E, and air-cases F of the boats A and 35 B are constructed so that they can be removed from the said boats in the form of a raft, as shown in Fig. 3, each raft being fully equipped with oars, masts, sails, and the usual equipment. The means for securing 40 the structure forming the thwarts, seats, and air-cases to the shell of the boat consist of eyes e and bolts e'. When not in use, the said structures, with their equipment, can be stowed upon one another on the top of the 45 deck-house H. The inner boat C is a boat of the usual construction equipped in the usual way.

To lift the boats one out of the other, I use two jibs, one at each end of the boat, and 50 lift the jibs by means of a toothed rack and pinion or like gear. In the drawings, J J

are the jibs. They are hinged at i i to carriages h h. These carriages h h slide on upright standards I I by means of the toothed racks h' h' and pinions k k. The boat-tackles 55 K K are attached to the heads of the jibs J J, and the lower blocks of the tackles are provided with eyes p, through which the bolts m at the ends of the boat pass. These bolts m may, to release the boat, be withdrawn in 60 any suitable way—for example, by means of rods n n, placed along the gunwale of the boat and worked by a lever n', as shown.

To launch a boat, the ends of the tackles K K are secured to the jibs J J, and by turning the pinions K K by means of their winch-handles K' K' the jibs J J and the boat attached or hung from them are raised until the boat is clear of the containing-boat. The jibs are then swung outward and lowered into the 70 position shown in dotted lines in Fig. 2, and the boat is then lowered into the water in the usual way. The boat can be lowered first from the jibs J J into position to embark the passengers from the lower deck a, and 75 then lowered into the water, or the passengers can enter the boat before leaving the containing-boat. After the boat C has been raised out of the boat B and while the passengers are embarking in it the raft B', consisting of the thwarts D and air-cases F of the boat B, is removed from the top of the deck-house H and placed in and secured to the shell of the boat B and then it may be launched in like manner to the boat C. Again, 80 when the boat B has been removed from the boat A, the raft A', consisting of the thwarts D, seats E, and air-cases F of the boat A, is placed and secured therein and it is ready 85 for use.

I would have it understood that although I have shown and described a set of jibs or davits suitable for launching boats when stowed in multiple and according to my invention, any suitable known kind of jib or 95 davit may be used to launch the boats or to place the rafts consisting of the thwarts D, seats E, and air-cases F in the boats. The said rafts may also be used by themselves as rafts in cases of emergency.

I am aware that it is not new to house boats one inside another, the under boat being pro-

vided with hinged seats and thwarts so arranged as to be folded and stowed in such a manner as to permit the smaller boat being set in place within the larger one; but this I do not claim, and I am not aware that prior to my invention a boat has been provided with thwarts, seats, and air-cases connected to constitute a raft separate from the boat-shell and removable therefrom to permit the housing therein of another boat-shell or boat, whereby the several boat-shells and rafts are, separate and independent of each other, so that the rafts composed of seats, thwarts, and air-cases can be used alone or be placed in the boat-shells when required.

Having now particularly described and ascertained the nature of my said invention and in what manner the same is to be performed, I declare that what I claim is—

1. The combination, with a ship's boat-shell, or a plurality of boat-shells adapted to be housed or stowed one within the other, of a separate raft-like structure or structures constituting the thwarts, seats, and air-cases of said boat shell or shells and capable of being used with such boat shell or shells or separately, substantially as set forth.

2. A ship's boat consisting of a shell and a separate raft-like structure comprising the thwarts, seats, and air-cases, said structure being provided with means, as described, by which the structure is secured to the shell, whereby boats of varying length and beam are capable of being stowed one within another, and, when required, fitted with said structure, or, in cases of emergency, said structure is capable of being used as a raft and independently of the boat-shell, as set forth.

3. In combination with the shell of a ship's boat, the raft-like structure herein described, comprising the thwarts D, seats E, and air-cases F, said structure being adapted to be fitted in and secured to the said shell, or to be used separately as a raft, substantially as set forth.

ARCHIBALD THOMSON DEWAR.

In presence of—

ERNEST RICHARD ROYSTON,
JAMES ANDREW COUBROUGH,
Both of 15 Water Street, Liverpool.
